R. F. TIBBETTS.

SHAVING BRUSH.

APPLICATION FILED FEB. 21, 1920.

1,396,474.

Patented Nov. 8, 1921.

UNITED STATES PATENT OFFICE.

RAYMOND F. TIBBETTS, OF CHICAGO, ILLINOIS.

SHAVING-BRUSH.

1,396,474.

Specification of Letters Patent. Patented Nov. 8, 1921.

Application filed February 21, 1920. Serial No. 360,511.

To all whom it may concern:

Be it known that I, RAYMOND F. TIBBETTS, a citizen of the United States, residing in Chicago, in the county of Cook and State of Illinois, have invented a new and useful Improvement in Shaving-Brushes, of which the following is a specification.

This invention relates to self-feeding shaving brushes and, while it has more particular reference to the provision of a shaving brush for containing and feeding shaving powder, it will be apparent that certain of its features may be usable in the feeding of other shaving materials.

A principal object of my invention is the provision of a shaving brush which may contain shaving soap in powdered form and insure the accurate feed of desired and appropriate amounts of it. The feeding of soap of this character in a self-feeding shaving brush presents peculiar difficulties because of the fact that the soap when in powdered or granular form does not readily fall into feeding devices of the usual character. My invention contemplates, among other features, the provision of positive means for abstracting the charges to be delivered to the bristles.

Another difficulty in the use of shaving powders in self-feeding brushes has resulted from the increasing of the tendency of the material to cake or compact itself into a solid mass upon the admission of any moisture into the powder reservoir and my invention contemplates as a further important feature the provision of a delivering device which will be moisture excluding.

The invention has for a further important object the provision of a shaving brush of the character described of simple, cheap construction, capable of easy operation, and consisting of parts so constructed and arranged as to prevent the necessity of frequent repair or replacement.

Numerous other objects and advantages of the invention will be apparent as it is better understood from the following description, which taken in connection with the accompanying drawings discloses a preferred embodiment thereof.

Referring to the drawings,—

Figure 1 is a side elevation of a shaving brush embodying my present invention;

Fig. 2 is a central, longitudinal sectional view thereof;

Fig. 3 is a view similar to Fig. 2 with the parts arranged in different positions;

Fig. 4 is a section taken substantially on the line 4—4 of Fig. 3;

Fig. 5 is a section taken on the line 5—5 of Fig. 3;

Fig. 6 is a section taken substantially on the line 6—6 of Fig. 3; and

Fig. 7 is a perspective view of the feeding sleeve.

For the purpose of illustrating my invention I have shown on the drawing a shaving brush having the usual tuft of bristles 11 secured in a handle 12, which handle provides a reservoir for the holding of shaving powder. The handle consists of a tubular body 13 of metal or other suitable material fast at its lower end in suitable fashion in the brush head 14. This brush head is provided with a central opening 15 in which the tuft of bristles 11 is secured. The tubular reservoir body is provided with a tapered or conical lower end 16 through which a tube 17 extends. This tube is fastened in the conical end and extends through the base 18 of the tuft providing thereby a portion extending out a substantial distance from the lower or feed end of the reservoir. Just above the feed end of this reservoir the tube is provided with perforations 19 in its side, which as will be presently described permit the soap material 21 to pass through into the inside of the tube where it may drop down into the bristles or be pushed down by a plunger provided for the purpose.

This plunger consists of a rubber body 22 fitting snugly within the tube and mounted upon the threaded end 23 of the plunger rod 24. The top of the body 13 of the reservoir is closed by a removable cap 25, having a central opening 26 through it. The plunger rod 24 extends through this opening and is provided at its outer end with a hand piece or button 27 to facilitate manipulation.

I provide means in the embodiment of my invention shown on the drawing both for insuring that at each manipulation of the plunger soap powder will enter through the perforations in the tube and also insuring that the charges entering will be the

predetermined amount desired. This means consists of a sleeve 28 having a sliding fit about the tube. Near its bottom the material of the sleeve is cut and bent out in the 5 form of fins 29 which scrape the powder from the body and cause it to slide down the fins and through the perforations. At the top the sleeve extends above the end of the tube and is provided with a cap 31 having 10 a central perforation through which the plunger rod 24 extends. Two collars 32 and 33 are fixed upon the plunger rod, one of these collars 32 being provided between the cap 31 of the sleeve and the cap 25 of the 15 reservoir, and the other 33 being located within the tube and at the upper end of the plunger.

In service the action of the brush is as follows: Fig. 2 shows the arrangement of 20 the parts in normal relation and this is the relation they assume after each use of the brush. To supply soap to the brush the finger piece or button 27 is lifted moving the plunger upwardly so that it uncovers the 25 ports or apertures in the tube. As it nears the top of its stroke the collar 33 is brought into engagement with the cap 31 and further lifting movement, which is slight, causes elevation of the sleeve to the position 30 shown in Fig. 3. In this movement the fins scrape off and cause the desired minute amount of powder to enter within the tube and immediately thereafter the sleeve closes the ports 19. Downward movement of the 35 plunger is next accomplished by returning the button 27 to its normal position, pushing the plunger down and back to the position shown in Fig. 2, ejecting all of the powder into the bristles. As the plunger nears the 40 bottom of its stroke the collar 32 on the plunger rod engages the outer surface of the cap 31 and pushes the sleeve back to normal position. The upward movement of the plunger is of course limited by engagement of the collar 32 with the inner face of the cap 25. In order that the sleeve and 45 tube may be maintained in relation to produce the desired relation between ports or apertures 19 and the fins 29 of the sleeve, I provide deformations 34 and 35 in the tube and sleeve respectively as may be seen in viewing Fig. 4. The deformation 34 in the tube extends merely a limited distance, being confined to the portion of the tube 50 within the reservoir.

The rubber plunger fits with sufficient tightness in the tube to prevent leakage of moisture back into the powder and should the brush be wet before the plunger is manipulated and the soap applied to the 60 bristles return of the plunger to normal position in the soap delivering action wipes the inside of the tube dry, much after the manner of a window squeegee. The action 65 of the parts in delivering the powder is such

that danger of water being admitted to the reservoir through the brush is negligible.

I prefer to inclose the handle forming the reservoir within a covering sheet of leather 36 and to provide a similar sheet of leather 70 37 for the cap.

It is thought that the invention and many of its attendant advantages will be understood from the foregoing description, and it will be apparent that various changes may 75 be made in the form, construction and arrangement of the parts without departing from the spirit and scope of the invention or sacrificing all of its material advantages, the form hereinbefore described being 80 merely a preferred embodiment thereof.

I claim:

1. A shaving brush, comprising a tuft of bristles, a handle providing a reservoir for 85 shaving material, a tube opening into said tuft of bristles and extending into said reservoir and having perforations near the end of said reservoir adjacent said tuft of bristles, a plunger movable in said tube, and means for scraping a quantity of shaving 90 material from the material in said reservoir and feeding the same through said perforations.

2. A shaving brush, comprising a tuft of bristles, a handle providing a reservoir for 95 shaving material, a tube opening into said tuft of bristles and extending into said reservoir and having perforations near the end of said reservoir adjacent said tuft of bristles, a plunger movable in said tube, and 100 means slidable on the exterior surface of said tube for alternately covering said perforations and uncovering them for feeding powder therethrough.

3. A shaving brush, comprising a tuft of 105 bristles, a handle providing a reservoir for shaving material, a tube opening into said tuft of bristles and extending into said reservoir and having perforations near the end of said reservoir adjacent said tuft of bristles, a plunger movable in said tube, and 110 means for alternately covering said perforations and uncovering them for feeding powder therethrough, said means being movable with the plunger during the latter portions of its movements in said tube.

4. A shaving brush, comprising a tuft of bristles, a handle providing a reservoir for 115 shaving material, a tube opening into said tuft of bristles and extending into said reservoir and having perforations near the end of said reservoir adjacent said tuft of bristles, a plunger movable in said tube, and 120 means slidable on the exterior of said tube and actuated by said plunger for alternately 125 covering said perforations and uncovering them for feeding powder therethrough, said means being movable by the plunger rod.

5. A shaving brush, comprising a tuft of bristles, a handle providing a reservoir for 130

shaving material, a tube opening into said tuft of bristles and extending into said reservoir and having perforations near the end of said reservoir adjacent said tuft of bristles, a plunger movable in said tube, and a sleeve embracing said tube, said sleeve and said plunger alternately closing said perforations in said tube.

6. A shaving brush, comprising a tuft of bristles, a handle providing a reservoir for shaving material, a tube opening into said tuft of bristles and extending into said reservoir and having perforations near the end of said reservoir adjacent said tuft of bristles, a plunger movable in said tube, and a sleeve embracing said tube, movable by the plunger and having fins for insuring feeding of the soap material.

7. A shaving brush comprising in combination, a tuft of bristles, a handle providing a reservoir for shaving material, a tube carried by said handle opening at one end into said tuft of bristles and having its other end extending into said reservoir, said tube having perforations near the end of said reservoir adjacent said tuft of bristles, a plunger mounted for longitudinal movement in said tube, and a sleeve slidably mounted on the exterior of said tube, said plunger having means adapted to engage and slide said sleeve when the plunger is moved to its uppermost position, said sleeve carrying means for abstracting a quantity of shaving material from said reservoir and delivering it through the perforations in said tube during its upward movement,

said abstracted material being ejected from said tube to said tuft of bristles upon the downward stroke of the plunger.

8. A shaving brush comprising a tuft of bristles, a handle providing a reservoir for shaving material, a tube opening into said tuft of bristles and extending into said reservoir and having perforations near the end of said reservoir adjacent said tuft of bristles, a plunger movable in said tube, and a sleeve embracing said tube and movable by the plunger, said sleeve carrying means for feeding the soap material through said perforations and means carried by said tube and said sleeve to prevent rotation of one with respect to the other.

9. A shaving brush comprising a tuft of bristles, a handle providing a reservoir for shaving material, a tube opening into said tuft of bristles and extending into said reservoir and having perforations near the end of said reservoir adjacent said tuft of bristles, a plunger movable in said tube and having a resilient sleeve adapted to prevent the access of moisture from the bristles to said reservoir; a sleeve slidably embracing said tube and having openings adapted to register with the perforations in said tube, said plunger having means adapted to engage and slide said sleeve when the plunger is moved to its uppermost position, said sleeve and said plunger being adapted to alternately close said perforations in said tube.

RAYMOND F. TIBBETTS.
